UNITED STATES PATENT OFFICE.

HARRY OSTROVSKY, OF LONDON, ENGLAND.

EXERCISING APPARATUS FOR USE BY MUSICIANS FOR DEVELOPING THE MUSCLES OF THE HAND.

1,136,481.

Specification of Letters Patent.

Patented Apr. 20, 1915.

Application filed September 11, 1914. Serial No. 861,268.

To all whom it may concern:

Be it known that I, HARRY OSTROVSKY, a subject of the Emperor of Russia, residing at 50 Leinster Gardens, Bayswater, London, England, have invented a new and useful Exercising Apparatus for use by Musicians for Developing the Muscles of the Hand, of which the following is a specification.

My invention relates to apparatus for use by violinists for exercising muscles brought into use when playing instruments, of the kind wherein spring plates or keys are employed on which the fingers of the left hand of the user operate and which are arranged to slide along a bar, frame or stem representing the key board of the instrument.

According to my invention I make the plates or keys so that they are removable from the key board or finger board and the resistance of the springs can be varied by removing and replacing the springs or by the provision of means for adjusting such tension thereof. The part of the frame, bar or stem in which slide the plates or keys is removably connected to the part carrying the chin-rest so that the said parts can be detached and joined together at a right angle, in which position the chin-rest can then serve as a support for the hand, wrist or fore arm and the apparatus can then be used for exercising the muscles used by pianists, the rest or support being movable along the bar or stem in order that its position may be adjusted to the user's requirements. When the apparatus is required for use by pianists it is advantageous to employ two similar parts of the frame carrying the keys or plates which would represent the white and black keys respectively of a piano, such parts being secured together.

Means are provided for stopping any one or more of the keys or plates from being actuated by the fingers in order to develop independence of action of the other fingers. Upon the bar or stem in proximity to the rest or support I provide an adjustable spring device in which the fingers or thumb can engage to afford lifting exercise therefor.

In practice the part of the frame in which the keys or plates are located is formed tubular with a longitudinal slot having an enlargement through which the keys are introduced, the keys being made with clamping nuts which grip the edges of the slot and

receive the stems of the pistons of the keys beneath which are the springs, the piston-stems being marked with divisions to indicate the pressing power exerted by the fingers and the tension of the springs being adjusted by screws working in the bottoms of the clamping portions; additional springs may also, if required, be coiled around the piston-stems.

A key of the described construction can be used in the hand separately from the rest of the apparatus in order to exercise the fingers, the springs forming a resistance to the pressure thereof.

To enable my invention to be fully understood I will describe it with reference to the accompanying drawing, in which:

Figure 1 is a longitudinal elevation of a hand-exercising apparatus constructed according to the invention, the parts being in position for use by violinists. Fig. 2 is a plan of the same, and Fig. 3 is a transverse vertical section on the line 3—3, of Fig. 1. Fig. 4 is a vertical section of one of the spring plates or keys. Fig. 5 is a plan of the apparatus with the parts in position for use by pianists. Fig. 6 is a plan illustrating the modified arrangement of the apparatus for use by pianists. Fig. 7 is a transverse vertical section on the line 7—7 of Fig. 6. Fig. 8 is a vertical section of one of the keys designed for use in the hand separately from the rest of the apparatus. Fig. 9 is a side elevation of the chin-rest or hand support with the device for affording lifting exercise for the fingers. Fig. 10 is a transverse vertical section on the line 10—10 of Fig. 9. Figs. 4 and 8 are drawn to a larger scale than the rest of the figures.

Referring to Figs. 1 to 4, *a*, *a* are the spring plates or keys and *b*, *c* indicate the bar, frame or stem representing the key board of a musical instrument the part *b* in which slide the keys *a* being connected to the part *c* carrying the chin-rest *d* by means of a screw threaded hole *e* in the former designed to receive the screw threaded end of the latter so that the said parts can be detached and joined together at a right angle as shown in Fig. 5 in which position the chin-rest *d* can then serve as a support for the hand, wrist or fore-arm and the apparatus can then be used for exercising the muscles used by pianists, and supporting feet *b* for the part *b* are attached

to the latter by screws b^2 as indicated by the dotted lines in Figs. 1 and 2 and full lines in Figs. 3 and 5 for supporting the frame b when said frame is in position at right angles to the part c . The said feet are obviously not required when the apparatus is used by violinists or the like. The part b of the bar, frame or stem is made with an aperture f midway of its length as shown in Fig. 1 in which can slide the other part c carrying the rest or support d so that the position of the latter can be adjusted to the user's requirements. The part b is formed tubular as shown, g being the longitudinal slot therein, fitting a neck h on the body of the keys so that they can be slid along the said slot, and i being the clamping nuts screwing on to the said body and adapted to grip the edge of the slot g and receive the stems j of the pistons j^1 of the keys a , as clearly shown in Fig. 4, in which h is the spring beneath the piston j^1 . The piston-stems j may be marked with divisions (not shown) to indicate the pressing power exerted by the fingers. l is the screw working in the body or bottom of the clamping portion of the key and by turning which the tension of the spring h can be adjusted. m is the additional spring coiled round the piston-stem j and which may be used, or not, as required. Instead of the tension of the spring h being adjusted by operating the screw l , the resistance to pressure of the keys can obviously be varied by removing the springs h and m and replacing them by others of different strength. n is the enlargement of the slot g , through which the keys d are introduced into, or removed from, the tubular part b of the bar, frame or stem of the apparatus.

As heretofore stated it is preferable to provide a scale or divisions (not shown) on the tubular part b of the frame to indicate the distance apart to which the keys are moved and secured, and when it is required to stop any one or more of the keys a from being actuated by the fingers in order to develop independence of action of the other fingers, the springs m and h are removed from such keys so that the pistons thereof will drop and be inoperative.

The construction of the modified apparatus, for the use of pianists, illustrated in Figs. 6 and 7 is precisely the same as that hereinbefore described with reference to Figs. 1 to 5 except that two similar parts b of the frame are connected together, and carry keys a representing the white and black keys, respectively, of a piano.

It is obvious that, if required, a key a can be used separately from the rest of the apparatus, for exercising the fingers by placing the base of the key, (provided with a thimble o having a rubber pad or disk as shown in Fig. 8) in the palm of the hand

and pressing the piston j^1 with the fingers or thumb against the action of the springs.

The device illustrated in Figs. 9 and 10 for affording lifting exercise for the fingers and thumb and which I provide upon the bar or stem c in proximity to the rest or support d consists of a sleeve q which can be slid to any desired position on the said bar and then secured in said position by means of a pressure screw r . The sleeve q carries a stirrup s having attached thereto a loop t of leather or other suitable material, which stirrup can be moved up and down a pin or rod u depending from the sleeve q against the action of a spring v on the said pin or rod so that, with the hand wrist or fore arm of the user resting on the support d , any one of the fingers or the thumb can engage the loop t and exercise its lifting power against the resistance of the spring which can be varied by unfastening the nut w on the rod or stem u and removing the said spring and replacing the same by another spring of different tension, or by screwing the nut up or down upon the said rod or stem.

Claims.

1. A finger exercising apparatus comprising a key board, keys provided upon said key board, and means for adjusting said keys longitudinally of said key board.

2. A finger exercising apparatus comprising a key board, keys provided upon said key board, means for adjusting said keys longitudinally of said key board, and a part carrying a support also connected to said key board.

3. A finger exercising apparatus comprising a key board, keys provided upon said key board, and means for detachably connecting said keys to and for adjusting the same on said key board.

4. A finger exercising apparatus comprising a key board, and a part carrying a support, said support carrying part being adapted to be detachably secured either to one end of said key board or to the center thereof.

5. A finger exercising apparatus comprising a key board, a part carrying a support, and means for detachably securing said support carrying part either to one end of said key board or to the center of the same.

6. A finger exercising apparatus comprising a key board, a part carrying a support, and means for detachably securing said support carrying part either to one end of said key board or to the center of the same, said central connecting means comprising an aperture provided in said key board intermediate its ends, in which said support carrying part is adapted to be inserted.

7. A finger exercising apparatus comprising a key board consisting of a tube having a slot, and keys provided on said key board.

and having portions which engage said tube adjacent to said slot.

8. A finger exercising apparatus comprising a key board consisting of a tube having a slot provided with an enlargement, and keys provided on said key board and having portions which engage said tube adjacent to said slot.

9. A finger exercising apparatus comprising a key board consisting of a tube having a slot provided with an enlargement, keys provided on said key board, and clamping means provided upon said keys, whereby said keys are caused to grip the edges of said tube adjacent to said slot.

10. A finger exercising apparatus comprising a support, a key mounted in said support and having a body, a piston provided in said body and having a stem, means for exerting pressure on said piston, and a clamping nut provided upon the top of said body, the stem of said piston passing through said clamping nut.

11. A finger exercising apparatus comprising a support, a key mounted in said support and having a body, a piston provided in said body, a stem provided on said piston, a spring provided in said body, and exerting pressure on said piston, and a clamping nut provided upon said body through which the piston stem passes.

12. A finger exercising apparatus comprising a support, a key mounted in said support and being provided with a body, a piston provided in said body, a stem on said piston, a spring in said body and engaging said piston, a clamping nut provided

upon said body through which the piston stem passes, and means closing the bottom of said body and serving to regulate the tension of said spring.

13. A finger exercising apparatus comprising a key having a body, a spring and piston within said body, a clamping nut fitting the top of said body and having an aperture through which the piston stem works, and a spring upon the said stem co-acting with the spring of the said body and arranged to resist the pressure of the finger or thumb of the user.

14. A finger exercising apparatus comprising a bar carrying a support, a sleeve adjustably mounted on said bar, a pin depending from said sleeve, a spring provided upon said pin, a stirrup loosely mounted on said pin and adapted to move against the tension of said spring, and a loop connected to said stirrup and adapted to be engaged by the thumb or a finger of the user.

15. A finger exercising apparatus, comprising a bar carrying a support, a sleeve adjustably mounted on said bar, a pin depending from said sleeve, a spring provided upon said pin, a stirrup loosely mounted on said pin and adapted to move against the tension of said spring, a loop connected to said stirrup for engagement by the thumb or a finger of the user, and means for adjusting the tension of said spring.

HARRY OSTROVSKY.
